CLOTH-CLAMP.

1,307,606.

Specification of Letters Patent. Patented June 24, 1919.

Application filed January 14, 1918. Serial No. 211,704.

To all whom it may concern:

Be it known that I, HUGO O. WIEGAND, a citizen of the United States, and resident of Philadelphia, county of Philadelphia, and State of Pennsylvania, have invented an Improvement in Cloth-Clamps, of which the following is a specification.

My invention has for an object the construction of an automatic cloth clamp for employment in textile machinery, and more especially tentering machines, which shall be effective in its operation and proof against the working upward of grease or oil from the chain structure of which it is a part and soiling the fabric while in the act of being clamped in position and while in the custody of the clamp during manipulation in the machine.

Heretofore cloth clamps for textile machinery have been made with brass or bronze cast plates provided with projections and fitted to the surface of the cast iron base of the clamp, but experience has demonstrated that while the facing of the base of the clamp with brass or bronze is an advantage from a structural standpoint it has been undesirably costly and moreover required modes of attachment which have permitted leakage of oil or grease to the surface of the plate and thereby caused injury to the fabric being subjected to treatment by machines, such as tentering machines in which large quantities of these clamps were employed. It is therefore also the object of my invention to provide a construction of cloth clamp in which the facing plate of brass or bronze may be formed of stamped sheet metal having a flanged and grooved edge to engage and lock with the cast base of the clamp thereby embodying lightness and cheapness coupled with accuracy as to shape and strength of attachment, and also to present a finished surface without requiring surfacing by machine work, whereby my improved clamp is more effective in its operation and less costly to produce.

My object is further to so shape the stamped sheet metal plate that it will hook over the front edge of the iron casting of the clamp base and be held in position by a single rivet in the rear of the plate whereby there shall be no screw or rivet holes extending upward to the surface of those portions of the plate over which the cloth is required to lie or be moved, the result being that

there is less liability to soil the fabric by oil or grease.

My invention also consists of improvements hereinafter described whereby the above objects and results are attained, said improvements comprising certain organization and combination of parts which are fully described hereinafter and more particularly defined in the claims.

For the purpose of illustrating my invention, I have shown in the accompanying drawings the embodiment thereof which is at present preferred by me, since the same is in form to give satisfactory and reliable results, but it is to be understood that the several instrumentalities of which my invention consists, can be variously arranged and organized and that my invention is not limited to the precise arrangement and organization of the instrumentalities herein shown and described.

Referring to the drawings Figure 1 is a front elevation of a cloth clamp embodying my improvements; Fig. 2 is a cross sectional view of the same taken on line 2—2 of Fig. 1; and Fig. 3 is a perspective view of the stamped sheet metal clamping plate removed from the base of the clamp.

2 represents one of the chain links forming the carrying part of the clamping device which is cast integral therewith. 3 is the base of the clamp and forms an extended surface immediately above the link 2, and said base is provided with the usual overhanging arms 8 whose free ends extend slightly in advance of the front edge of the base of the clamp. The upper surface of the base may be roughly machined to make it flat and the front edge may be machined to the shape indicated at 3^a in Fig. 2, the lower part of this portion 3^a being undercut as illustrated. 5 is a stamped sheet metal plate, preferably of brass or bronze and is provided at its forward or side end with a downwardly and inwardly bent portion 7 providing a longitudinal groove 7^a which is of the exact shape of the cross section of the machined edge 3^a of the base of the clamp. This plate 5 is fitted tightly upon the portion 3^a of the base 3 and said portion 3^a is snugly received in the longitudinal groove 7^a of the plate. The plate is pressed tightly in position and riveted in such position by a single rivet 17 extending upward through the base 3 and through a countersunk hole 110

18 in the plate 5 immediately in the rear thereof. In this manner the plate 5 is securely held in position without any rivets or screws in the forward part of the plate over 5 which the cloth F is required to move, or upon which it rests, as will be understood by reference to Fig. 2. 9 is a pivoted clamping jaw and is loosely journaled upon the shaft 11 which extends through the over- 10 hanging ends of the arms 8. The clamping jaw 9 has its hinged ends extending upon the outer sides of the arms 8 so as to be held against longitudinal shifting, while at the same time it is free to oscillate about 15 the shaft 11 as a center. This jaw 9 is also provided at its upper part with an arm 12 which is adapted to be operated upon by cams in the machine for moving the arm out of clamping position (Fig. 2) or for releasing 20 said arm and permitting its clamping edge 10 to be depressed to clamp the fabric F between said edge and the upper surface of the clamping plate or bed 5. As shown in the drawings, the rear part of the clamping 25 jaw 9 is provided with an arm 13 in which a controlling trip 14 is pivoted by the transverse pin 16. The rear part of the trip 14 rests upon the plate 5 and the forward portion at the other side of the pivot pin 16 is adapted to rest upon the fabric F before it is moved outward to the final or clamping position. Immediately below the 30 part 15 of the trip 14 is a slotted portion 6 in the plate 5 and immediately under this is a wider slot 4 in the casting of the base 3. These slotted portions permit the end 15 of the trip 14 passing downward when the fabric F is pulled forward, to such an extent as to release the trip, at which time the clamping 35 jaw 9 is permitted to swing down to clamping position and grip the edge of the fabric upon the plate near its outer edge and in front of the slotted portion 6 thereof. The trip device and slots in the base plate 40 are well known and I do not make any claim thereto, my improvements being directed solely to the construction and adaptation of the stamped sheet metal plate 5 to the clamp of the general construction shown, whereby 45 50 55 60 65

It will be understood that by the elimination of screws and rivets in the forward part of the plate I omit channels through which grease and oil may leak upwardly to the clamping surface; and by providing the front edge of the plate with a downwardly extending flange bent inward as at 7 to provide a grooved portion 7^a I greatly strengthen the plate and may therefore employ a sheet metal plate of materially less thickness than has heretofore been possible. By the construction employed by me, I am further enabled to so hold the plate 5 throughout its full width upon the over-

hanging front portion 3^a of the clamp bed that there is no possibility of the plate buckling or curving between its side edges, but on the contrary is held perfectly flat and therefore provides an ideal clamping surface 70 with which the clamping edge 10 of the jaw 9 is permitted to coöperate; and I am therefore enabled to use a relatively thin plate without fear of uneven pressure upon the cloth with the resulting danger of cutting 75 the same which otherwise would occur. Furthermore, the shape of the front portion of the plate, in completely extending over the front edge 3^a of the bed, prevents any exposed seam adjacent to the cloth as has heretofore been the case and from which seam grease and oil have worked their way to the surface of the plate and soiled the fabric. My improvement entirely overcomes this tendency of the grease to find its 80 85 way to the fabric.

Another advantage, which I secure by my improvement, resides in the fact that the plate 5, being of stamped sheet metal, the plates of all the clamps will be identical and interchangeable; and because of this, the clamps may be readily repaired by substituting new plates 5 for worn plates and moreover such repairs may be made on the machine without necessitating the sending 90 95 of the clamps to a machine shop.

The plate 5, being of stamped sheet metal is quite smooth when received from the dies and does not require any surface finishing. Its operating surface of the brass or bronze 100 sheet, being the normal hard rolled surface thereof, is more durable than if the plate had been cast and then ground, milled or planed, as has heretofore been the practice.

It will now be apparent that I have de- 105 vised a novel and useful construction which embodies the features of advantage enumerated as desirable, and while I have in the present instance shown and described the preferred embodiment thereof, which has 110 been found in practice to give satisfactory and reliable results, it is to be understood that I do not restrict myself to the details, as the same are susceptible of modification in various particulars without departing 115 from the spirit or scope of the invention.

Having now described my invention, what I claim as new and desire to secure by Letters Patent, is:

1. In a cloth clamp for textile machines, the body having a base formed with a flat top and an extended front edge, combined with a stamped sheet metal clamping plate having an extended flat surface resting upon the base and a front portion bent downward and backward to form a longitudinal groove which tightly receives the extended front edge of the base, means for connecting the rear portion of the clamping plate tightly with the base to prevent the plate lifting at 120 125 130

the rear or shifting forward upon the base, and a clamping jaw hinged to the body above the clamping plate and adapted to contact therewith near its forward edge.

5 2. A detachable clamping plate for a cloth clamp comprising a stamped sheet metal plate wide at its front edge and narrowed at its rear edge and having an aperture near its rear edge, a slot intermediate of said edges, and said plate further having its front edge bent downward and backward to

form a longitudinal groove of approximately uniform cross section to facilitate attachment and to give rigidity to the clamping surface between the slot and front edge. 15

In testimony of which invention I hereunto set my hand.

HUGO O. WIEGAND.
